UNITED STATES PATENT OFFICE.

CHESTER LOMBRA, OF MERIDEN, CONNECTICUT.

MULTIFACED DOLL.

1,059,178.

Specification of Letters Patent. Patented Apr. 15, 1913.

Application filed August 5, 1912. Serial No. 713,371.

To all whom it may concern:

Be it known that I, CHESTER LOMBRA, a citizen of the United States, residing at Meriden, in the county of New Haven and 5 State of Connecticut, have invented certain new and useful Improvements in Multifaced Dolls; and I do declare the following to be a full, clear, and exact description of the invention, such as will enable others skilled 10 in the art to which it appertains to make and use the same.

This invention relates to improvements in dolls.

One object of the invention is to provide 15 a doll with a plurality of superposed movable faces so arranged that any one of them may be exposed when desired.

Another object of the invention is to provide 20 a doll having one fixed face with a plurality of movable faces disposed one over the other, the faces being so connected as to uncover the face desired to be exposed and position the face not in use out of sight.

Another object is to provide simple, efficient 25 and ornamental means for fastening the faces in operative position.

With these and other objects in view the invention consists of certain novel features of construction, combination and arrangement 30 of parts as will be hereinafter more fully described and claimed.

In the accompanying drawings; Figure 1 represents a front elevation of a doll equipped with this improvement and with 35 the faces arranged in superposed relation and the exposed face showing a pleased expression; Fig. 2 is a similar view showing a crying face; Fig. 3 represents a vertical section through the doll face and the dress 40 taken on the line 3-3 of Fig. 1 the body and head being shown in side elevation.

In the embodiment illustrated, a rag doll body 1 is shown having a head 2 fixed thereon and provided with a permanent face 3. 45 This face 3 is shown with a pleasing expression and is the foundation on which other faces to be described are superposed.

Any desired number of faces may be employed, three being here shown and numbered 50 4, 5, and 6 respectively. These faces 4, 5 and 6 are connected at their neck portion to the neck of the doll by sewing or in any other suitable manner, whereby, the faces may be turned down and hidden under 55 the clothing of the doll when not in use.

Normally these faces are arranged one under the other with the face 6 on the outside and are held in place by means of a bandeau 7 composed of celluloid or of any suitable material and preferably secured 60 at its ends to the neck of the doll by a pin or pintle 8 which hingedly connects the bandeau and permits it to be turned downward when desired for releasing the faces. This bandeau is held in operative 65 position by any suitable means, a pin 9 being here shown inserted through a hole in the bandeau and extended into the head of the doll. Any suitable ornamentation may be provided for the bandeau, a bow 10 being shown arranged at one side thereof. 70

The faces 4, 5 and 6 may represent crying, laughing or other expressions and when it is desired to expose one of them, those overlying are all folded downward and arranged under the dress of the doll out of sight. Bandeau 7 is then arranged in place over each of the faces to be exposed at the point where the face is supposed to join the head of the doll and said bandeau is there 80 secured by the pin 9 or otherwise. It is thus obvious that by removing the pin 9 and turning bandeau 7 downward any one of the other faces desired may be exposed and by replacing the bandeau and pin 9 said face 85 will be held securely in operative position.

While this invention is shown applied to a rag doll it is of course to be understood that it may be applied to any other doll, the principle being the same. 90

I claim as my invention;

1. A doll having a fixed face and a movable face hingedly connected thereto, said movable face being mounted to be superposed on said fixed face and to be removed 95 when desired.

2. A doll having a plurality of movably connected faces adapted to be superposed on each other and one only exposed at a time, and means for holding said faces in 100 operative position.

3. A doll having a plurality of movable faces adapted to be superposed on each other, and a bandeau pivotally mounted to hold said faces in operative position. 105

4. A doll having a plurality of movable faces adapted to be superposed on each other, a bandeau pivotally connected by its ends to the doll head and means for securing said bandeau in operative engage- 110

ment with the head and the face to be secured thereby.

5. A doll head having a plurality of faces hingedly connected to the neck portion thereof, in position to overlie each other and means for holding said faces in superposed relation.

In testimony whereof I have hereunto set my hand in presence of two subscribing witnesses.

CHESTER LOMBRA.
